SLICING MACHINE

William J. Campbell, Indianapolis, Ind., assignor
to American Slicing Machine Company, Chi-
cago, Ill., a corporation of New York

Application January 15, 1934, Serial No. 706,714

2 Claims. (Cl. 146—102)

My invention relates to an improvement in slicing machines, particularly of a type in which a knife is rotated at high speed. It has for one purpose the provision of improved sharpening means for such a knife. Another purpose is the provision of sharpening means which may be located in a completely shielded or enclosed position. Another object is the associating of the sharpening means with a guard plate positioned forwardly of the knife in such fashion that the guard plate and the cover therefor are practically flush. Another object is the prevention of the necessity of any forward projection of the guard plate, frame or cover for any distance forward of the cutting edge of the knife. Another object is the provision of improved means for securing the guard plate in position. Other objects will appear from time to time in the course of the specification and claims.

I illustrate my invention more or less diagrammatically in the accompanying drawings, where-

in—

Figure 1 is a front elevation;

Figure 2 is an enlarged section on the line 2—2 of Figure 1;

Figure 3 is an enlarged section on the line 3—3 of Figure 1;

Figure 4 is an enlarged section on the line 4—4 of Figure 1;

Figure 5 is a section on the line 5—5 of Figure 2;

Figure 6 is a partial plan view with parts broken away;

Figure 7 is a section on the line 7—7 of Figure 6;

Figure 8 is an enlarged section on the line 8—8 of Figure 1;

Figure 9 is a section on the line 9—9 of Figure 8;

Figure 10 is a form similar to Figure 4 illustrating one variant mounting or securing means for the guard plate; and

Figure 11 is a modified form of the structure shown in Figure 8.

Like parts are indicated by like symbols throughout the specification and drawings.

Referring to the drawings A generally indicates any suitable base from which may upwardly extend any suitable frame structure including the portion generally indicated as A¹ in Figure 2. A² indicates a knife sleeve which may also be associated with or secured to such base and frame portion. A³ indicates a motor mounted on said base.

A⁴ is a rotary knife which may be mounted for rotation in relation to the sleeve A² and which

is driven from the motor A³ as by the pulleys A⁵ and A⁶ and the belt A⁷.

B is a guard plate which masks most of the forward face of the knife A⁴. The axis of the knife is somewhat inclined from perpendicularity to the guard plate B so that the guard plate may penetrate the hollow of the knife. It is shown as terminating in an arcuate edge B¹. It is offset as at B², B³ to clear the knife edge. It is mounted upon the frame, for example, by notches B⁴ which seat upon supporting pins B⁵ between positioning members B⁶ which are spring thrust together as by the springs B⁷. The upper edge of the guard plate is provided with inwardly turned portions B⁸ B⁹ which, in Figure 4, are shown as provided with angular offsets B¹⁰. These portions B⁸ B⁹ extend over any suitable frame portions B¹¹, which may, for example, be integral with the frame A¹. When they are in the position in which they are shown in Figure 4, they are held in position as by securing leaf springs B¹² adjustably mounted on the members B¹¹ as by screws B¹³ passing through slots B¹⁴, and when pressure is not applied to it, the leaf spring B¹² is in the dotted line position of Figure 4 which permits ready insertion and removal of the upper edge of the guard plate B.

C indicates a cover which extends above the frame portions B¹¹. It is guided, for vertical movement, by dowel pins C¹ which may be mounted in the frame portion B¹¹ and which may penetrate suitable apertures C² in the cover C. These apertures are surrounded by bosses C³. These bosses and the pins C¹ are surrounded by coil springs C⁴ which tend to hold the cover C in the upper or dotted line position of Figures 1 and 4. When in this position, it is sufficiently high to permit the guard plate B to be rotated into or out of position. Assuming that the guard plate has been rotated into position beneath the springs B¹², then the operator can lower the cover into final or closed position by rotating a locking knob C⁵ with its screw threaded pin C⁶ which is in screw threaded relationship with a portion C⁷ of the frame portion B¹¹. Rotation of the knob C⁵ draws the cover C down against the springs C⁴ until it is in the full line position of Figures 1, 2 and 4. When in this position, it engages the upper curved end of each spring B¹² and moves it from the dotted line to the full line position of Figure 4, positively locking the upper edge of the guard plate in place. The parts are so proportioned, also, that the arcuate upper portion of each spring B¹² is constrained, by its engagement with the forward flange of the cover C, to direct

a rearward, as well as a downward pressure against the angular portion B¹⁰. The result is a very firm locking of the parts in position. However, an easy retrograde rotation of the knob C⁵ will quickly release the parts and the springs C⁴ will lift the cover C again into the dotted line position permitting a ready withdrawal of the upper edge of the guard plate B. Note that, as shown for example in Figures 2 and 4, the forward edge of the cover C is practically flush with the face of the guard plate B. It should be also noted that the springs B¹² are aligned by side aligning members or flanges B²⁰, as will be clear from Figure 7, the flanges B²⁰ extending far enough forwardly to engage each side of the guard plate projection B⁸. This will not merely prevent twisting of the springs B¹² but will also prevent any twisting or misalignment of the guard plate B or of its inward projection B⁸.

In order to sharpen the cutting edge of the knife, and sharpening is necessary at fairly frequent intervals, I provide a structure which includes a grinding member opposed to one side of the cutting edge and a burnishing member opposed to the other, this entire assembly being enclosed by the guard plate B and the rear frame portion A¹.

A²⁰ indicates an end wall of the frame which may be formed integrally with the rear wall A¹, which has bosses DD¹. These bosses are screw threaded to receive pins D² D³ which may be axially adjusted by rotation and which may be held in adjusted position by the rotation preventing screws D⁴. D⁵ indicates a flange extending forwardly from the rear frame member A¹, and formed as a guard for the driving mechanism. It stops short of the cutting edge of the knife and may be, in part, closed by a removable shield plate D⁶. This plate D⁶ is centrally apertured as at D⁷ to permit passage therethrough of the knife assembly. The member D⁵ is also provided with bosses D⁸ which slidably receive the ends of the pins D² D³.

Rotatably mounted upon the shaft D² is a boss E which is associated with a lever E¹. This lever has associated with it a boss E² in which is rotatably mounted a shaft E³ to which is secured the grinding or sharpening wheel E⁴ which is provided with a bevel portion E⁵ adapted to be opposed to the cutting edge of the knife. E⁶ indicates a spring which normally tends to impart a clockwise rotation to the lever E¹, referring to the parts in the position in which they are shown in Figure 2. This clockwise rotation is limited by the abutment E⁷ which is associated with a boss E⁸. Slidably mounted in the boss E⁸ is a pin E⁹ controlled by an exterior thrust knob E¹⁰. This pin has a transverse pin E¹¹ which engages the eccentric adjusting member E¹² on the lever E¹. It will be understood that normally the spring E⁶ holds the lever E¹ in the full line position of Figure 2 but that when the operator thrusts inwardly against the knob E¹⁰, the spring E⁶ is extended and the sharpening member E⁴ is thrust against the cutting edge of the knife in the proper sharpening position. To insure that it will be in proper position at the end of the thrust against the manual knob E¹⁰, the eccentric adjusting member may be employed. This eccentric member is held in position, for example, by the screw E¹³, which also acts as an anchor for the spring E⁶. E¹⁴ is an oiling fitting for the shaft E³.

It is also desirable, for example because of wear of the knife, to be able to adjust the sleeve

or boss E on the pin D². It will be observed as in Figure 1 that the diameter of the pins D² and D³ is substantially less than the diameter of the threaded portions. This results in the formation of a ledge or abutment against which the sleeve E and the corresponding sleeve G on the pin D³ may be held as by suitable collars D²⁰. Thus, axial adjustment of the pins D² and D³ also results in an adjustment of the location of the sleeves E and G radially of the cutting edge of the knife.

The sleeve or boss G, which is rotatably mounted upon the pin D³ carries a lever structure G¹ which is similar to the lever E¹. This lever structure includes a boss G² with its sleeve G³ in which rotates the shaft G⁴ of the burnishing member G⁵. G⁶ is an oil fitting. G⁷ is a spring which tends to hold the burnisher G⁵ in the position in which it is shown in full line in Figure 2 but which permits it to recede to the left and conform to the position of the knife when the lever G¹ is moved to the limit of its movement to the right. The lever G¹ is provided with an upwardly extending finger G⁸ with an associated ledge G⁹ adapted for engagement with the transverse pin E¹¹. The corresponding ledge E²⁰ is formed in the lever E¹ and the ledges G⁹ and E²⁰ hold the shaft E¹¹ in generally horizontal position in alignment with the members E¹² and G⁸. The lever G¹ is normally urged in a counter-clockwise direction, referring to the position of the parts in which they are shown in Figure 2, by the spring G¹⁰ which is secured to the end of a downward extension G¹¹ as by the screw head G¹². The location and arrangement of this spring, as shown in Figure 5, is such that its function is not disturbed by a movement of the sleeve G as a result of the axial adjustment of the shaft D³. The spring G¹⁰ is anchored to the headed anchorage member G¹⁴. G¹⁵ is an abutment, shown as a set screw, for limiting the counter-clockwise movement of the lever G¹, so that the burnishing member G⁵ will not strike the inner face of the guard plate B. When the operator wishes to use the burnisher, he pulls out on the knob E¹⁰. As a result, the shaft E¹¹ engages the finger G⁸ and imparts a clockwise rotation to the lever G¹, referring to the parts in the position in which they are shown in Figure 2. This clockwise rotation moves the burnishing member G⁵ into engagement with the face of the knife. It will be clear that the knob E¹⁰ and the pin E¹¹ are normally in neutral position. Each lever E¹ and G¹ has its own spring E⁶ and G¹⁰ normally drawing it against its respective abutment E⁷ or G¹⁵. When the operator thrusts on the knob, he resists the action of the spring E⁶ and engages the sharpener E⁴ with the knife. When he pulls on the knob, he resists the action of the spring G¹⁰ and engages the burnisher G⁵ with the knife.

I find it important to prevent the access of material, grease, bits of meat or the like, to the sharpening mechanism. The flange D⁵ must, of course, stop short of the knife, as will be clear from Figure 2, and there is a space between the forward edge of the flange D⁵ and the rear face of the guard plate B. The knife is given a counter-clockwise rotation, referring to the position of the parts as in Figure 1, this direction of rotation being indicated by the black arrow in Figure 1.

H generally indicates a refuse trough or goo pan which underlies the cutting edge of the knife and extends substantially rearwardly of the cutting edge. Its inner edge H¹ is in general

alignment with the edge of the flange D⁵, as will be clear from Figure 2. It closely approaches the edge of the cover plate D⁶, as is also clear from Figure 2. The scraper H² is herein shown as mounted on the guard plate B and this scraper will remove the maximum portion of the grease and scraps and will discharge them into the goo pan H. This scraper will be effective substantially to clear the forward face of the knife. I 10 may provide scraping means for the rear face of the knife, but I find it desirable also to have a cleansing device to prevent foreign material from entering to the rear face of the knife or the front face of the knife. This guard is generally indicated as H³, in Figures 8 and 11. In 15 the form of Figure 8, the member H³ is opposed only to the rear face of the knife. In both forms it has a rear edge portion H⁴, curved in cross section as at H⁵ and conforming quite closely to the contour of the knife. The member H³ is adjustable as by slots H⁶ through which pass locking screws H⁷ which penetrate a portion of the flange D⁵. In the form of Figure 11, there is also a forward extension H⁸ opposed to the front 20 of the knife.

Referring to Figures 1 and 6, J J¹ are tracks extending across the forward face of the machine. Slidably mounted upon them is the carriage J² which supports a work receiving tray J³. The 30 gauge plate J⁴ serves to gauge the thickness of the slices to be cut.

Referring to Figure 10, I have illustrated a variant form of locking means for the guard plate B, in which the inwardly turned portions B²¹ and 35 B²² terminate in upwardly inclined cam members B²³ which are adapted to be engaged by the lug or lugs B²⁴ integral with the cover member C. The parts are so proportioned that the lugs B²⁴ exert a downward, as well as a rearward, pressure 40 against the cam members B²³ of the guard plate B when the cover C is lowered into final or closed position by means of the locking knob C⁵.

It will be realized that whereas I have shown a practical and operative device, nevertheless 45 many changes may be made in size, shape, number and disposition of parts without departing from the spirit of my invention. It will be realized, in particular, that I do not wish to be limited to any precise form, location, or relationship of 50 abutments, springs and the like, but also that the levers E¹ and G¹ may be widely varied in form and relationship without departing from the spirit of my invention. I, therefore, wish my description and drawings to be taken as in a broad sense 55 illustrative or diagrammatic rather than as limiting me to the precise details disclosed.

I claim:

1. In a slicing machine having a base, a knife rotatably mounted on said base and means for actuating it, a housing extending upwardly from said base and about said knife, a guard plate closing the front of the housing and overlying a substantial portion of the face of the knife, a cover for said housing, mounted upon the upper portion thereof, guiding elements for said cover, interposed between cover and housing, yielding means tending normally to lift said cover, said guiding elements including limit means adapted normally to limit the upward movement of said cover in response to said yielding means, said cover thereby being maintained in a position upwardly spaced 10 from the top of the housing, and locking means adapted to move said cover downwardly into locked position, said guard plate being formed with locking portions adapted to penetrate between housing and cover when the cover is raised 15 by said yielding means, said locking portions being provided with offsets adapted to prevent movement of said guard plate when the cover is in closed position, and locking springs positioned upon the housing and located within the cover, 20 when the cover is in closed position, said springs having free ends adapted for a cramping engagement with the inside of the cover whereby, when the cover is in closed position, the springs are positively held by the cover in locking relationship 25 with said offsets.

2. A slicing machine having a base, a knife rotatably mounted on said base and means for actuating it, a housing extending upwardly from said base and about said knife, a guard plate closing said housing and overlying a substantial portion of the face of the knife, a cover for said housing mounted upon the upper portion thereof, laterally extending guiding and securing elements for said guard plate adapted to be interposed between the cover and housing in response to a tilting movement of the guard plate about its lower edge, yielding means tending normally to lift said cover, locking means adapted to move said cover downwardly into locked position against the guiding and securing portion of the guard plate, said locking means being adapted to limit the upward movement of the cover in response to the thrust of said yielding means and being of sufficient length to permit the cover to be vertically aligned 35 with the housing but spaced thereabove a sufficient distance to permit the ready lateral movement of the locking portion of the guard plate into and out of locking position between the cover and the housing. 40

WILLIAM J. CAMPBELL.
